Geo. P. Kammel.

UNITED STATES PATENT OFFICE.

BEN LIPPIS, OF CHANDLER, COLORADO.

DRILLING MACHINE.

Application filed October 25, 1921. Serial No. 510,380.

To all whom it may concern:

Be it known that I, BEN LIPPIS, a subject of the King of Italy, residing at Chandler, in the county of Fremont and State of Colorado, have invented certain new and useful Improvements in Drilling Machines, of which the following is a specification.

This invention relates to drilling machines, more particularly to devices of this class employed in mining operations, and has for one of its objects to provide an apparatus of this character capable of being supported from the walls of a shaft, lateral heading, drift, or other portion of a mine tunnel, or the like, and adjustable to direct the drill or other cutting implement in any direction.

Another object of the invention is to provide a device of this character capable of being manually operated, or adapted without material structural change for operation by any external power, such as an internal combustion engine, electric motor, or the like.

With these and other objects in view, the invention consists in certain novel features of construction as hereinafter shown and described and then specifically pointed out in the claims, and in the drawings illustrative of the preferred embodiment of the invention.

Figure 1 is a front elevation of the improved apparatus.

Fig. 2 is a longitudinal sectional view on the line 2—2 of Fig. 1.

Fig. 3 is a plan view of the parts shown in Fig. 1.

Figs. 4 and 5 are sections on the lines 4—4 and 5—5 of Fig. 1 illustrating the construction of the backing clutch devices of the apparatus.

The improved device comprises a portable outer oblong supporting frame formed with spaced side members 10 and 11, and end members 12 and 13, of any suitable material preferably of steel, of sufficient strength to withstand the strains to which it will be subjected.

Extending from the members 10 and 11 near their ends are brackets 14 apertured to slidably receive pointed anchoring rods 15, the latter adjustably supported in the brack-

ets by clamp bolts 16. The rods 15 at each end of the frame are coupled to head members 17, and supported centrally of each head member is a threaded centering pin 18, 55 each pin having a turning disk 19 as shown.

By this arrangement the outer frame may be rotatively supported between the walls of a mine shaft, drift, level or other "workings" within the range of the member 18. 60

After the main or outer frame has been adjusted to the required position, the members 15 will be adjusted to engage the supporting walls and thus hold the frame from rotation during the drilling action, as here- 65 after explained.

Formed in one edge of each of the side members 10 and 11 of the main or outer frame, are a plurality of inclined superposed rearwardly opening slots 19 providing seats 70 to adjustably support a shaft 20, the shaft having an operating handle 21 at one end and slotted or apertured at 22 at the other end to receive a turning bar or lever, if required. 75

Mounted to swing upon the shaft 20 between the side members 10 and 11 is an inner frame or housing including spaced side members 23 and 24 and spaced transverse members 25 and 26, the shaft 20 passing 80 through the side members 23 and 24, as shown.

Mounted to rotate upon the shaft 20 between the side members 23 and 24 are bevel gears 27 and 28, the latter having internally 85 toothed clutch rims 29 and 30 with the teeth 31 and 32 of the rims reversely directed, as shown in Figs. 4 and 5.

Mounted for rotation with the shaft 20 and within the clutch rims, are disk members 33 and 34 carrying spring held pawls 35 and 36 to respectively engage the ratchet teeth 31 and 32. 90

Supported for rotation upon the transverse member 25 is a smaller gear 37, the latter having a polygonal shaped aperture to slidably receive a drill rod 38 to correspond to the contour of the aperture of the gear, so that it will rotate with the gear while at the same time be movable longitudinally there- 95 through. 100

The transverse member 26 supports a stub

shaft or stud 39 and mounted on the stud is a compound gear element formed with a bevel gear 40 in constant engagement with the bevel gears 27 and 28, and with a rim 5 gear 41 in constant engagement with the smaller gear 37.

By this arrangement it is immaterial in which direction the shaft 20 is rotated, the drill rod will be rotated in but one direction.

Mounted for rotation through the side members 23 and 24 of the inner frame is a shaft 42 carrying winding drums 43, and coupled to the outer end of the drill 38 is a 15 cross head member 44. Chains 45 are connected respectively to the member 44 and to the drums 43.

By this arrangement longitudinal strain may be applied to the drill rod to feed it to 20 its work.

Coupled to the frame members 23 and 24 and to the member 12 of the outer frame, are supporting chains 46 to hold the inner frame in adjusted position.

25 Thus as the shaft 20 is adjusted in the seats 19 to dispose the inner frame in a higher or lower position, the chains 46 can be quickly adjusted to correspond with the movements of the inner frame to retain the 30 drill rod at any required angle relative to the frames.

The improved device is simple in construction, and can be quickly adjusted to any irregular formation of the walls of the drift 35 or tunnel in which the apparatus is to be employed.

The preferred embodiment of the invention is disclosed in the drawings and set forth in the specification, but it will be understood that any modifications within the 40 scope of the claimed invention may be made in the construction without departing from the principle of the invention or sacrificing any of its advantages.

45 What is claimed as new is:—

1. A drilling machine comprising a portable frame having superposed slots in the sides thereof forming aligning seats, an adjustable housing positioned in said support, 50 a gear rotatably mounted in the rear of the housing and formed with a polygonal shaped opening, a longitudinally shiftable drill formed with a polygonal shaped stem extending through said opening, a shaft extending through said housing and mounted 55 on a pair of aligning seats, said slots providing means for the vertical adjustment of said shaft and housing, a driven element supported at the rear of the housing and 60 meshing with said gear for rotating the drill, a pair of drive gears mounted on the shaft and meshing with said driven element, means for independently and detachably coupling the drive gears to said shaft, and a winding 65 shaft carried by the housing and having

flexible connection with said drill for shifting it longitudinally.

2. A drilling machine comprising a portable frame having superposed slots in the sides thereof forming aligning seats, an adjustable housing positioned in said support, 70 a gear rotatably mounted in the rear of the housing and formed with a polygonal shaped opening, a longitudinally shiftable drill formed with a polygonal shaped stem extending through said opening, a shaft extending through said housing and mounted on a pair of aligning seats, said slots providing means for the vertical adjustment of said shaft and housing, a driven element supported at the rear of the housing and meshing with said gear for rotating the drill, a pair of drive gears mounted on the shaft and meshing with said driven element, means for 75 independently and detachably coupling the drive gears to said shaft, a winding shaft carried by the housing and having flexible connection with said drill for shifting it longitudinally, and flexible connections between said housing and the top of said frame.

3. A drilling machine comprising a portable frame having superposed slots in the sides thereof forming aligning seats, an adjustable housing positioned in said support, 80 a gear rotatably mounted in the rear of the housing and formed with a polygonal shaped opening, a longitudinally shiftable drill formed with a polygonal shaped stem extending through said opening, a shaft extending through said housing and mounted on a pair of aligning seats, said slots providing means for the vertical adjustment of said shaft and housing, a driven element supported at the rear of the housing and meshing with said gear for rotating the drill, a pair of drive gears mounted on the shaft and meshing with said driven element, means for independently and detachably coupling the drive gears to said shaft, 85 a cross head connected to the rear of said drill, a winding shaft mounted in the rear of said housing, and flexible connections between said winding shaft and cross head and winding on the shaft for shifting the drill.

4. A drilling machine comprising a portable frame having superposed slots in the sides thereof forming aligning seats, an adjustable housing positioned in said support, 90 a gear rotatably mounted in the rear of the housing and formed with a polygonal shaped opening, a longitudinally shiftable drill formed with a polygonal shaped stem extending through said opening, a shaft extending through said housing and mounted on a pair of aligning seats, said slots providing means for the vertical adjustment of said shaft and housing, a driven element supported at the rear of the housing and meshing with said gear for rotating the 95 drill.

drill, a pair of drive gears mounted on the shaft and meshing with said driven element, means for independently and detachably coupling the drive gears to said shaft, a cross head connected to the rear of said drill, a winding shaft mounted in the rear of said housing, flexible connections between said winding shaft and cross head and winding on the shaft for shifting the drill, and flexible connections between the upper end of the frame and the rear end of the housing.

In testimony whereof, I hereby affix my signature hereto.

BEN LIPPIS.
